GRID CASTING MACHINE

Alvy C. Yerkey, Maywood, Ill.

Application November 3, 1939, Serial No. 302,791

2 Claims. (Cl. 22—57)

This invention relates to a grid casting machine and is particularly useful in the forming of storage battery grids and like grids.

An object of the invention is to provide a greatly simplified structure whereby grids may be expeditiously and accurately formed, automatic means for opening and closing the grid molds being provided. A further object is to provide a grid forming machine equipped with a rotatable mold supporting platform, means being provided for heating the molds and for reciprocating them in the grid forming operation. Other specific objects and advantages will appear as the specification proceeds.

The invention is illustrated, in a preferred embodiment, by the accompanying drawing, in which—

Figure 1 is a plan view of a grid forming machine embodying my invention, the greater portion of the top part of the machine being broken away; and Fig. 2, a transverse sectional view taken substantially along the central line of the machine.

In the illustration given, A designates a base equipped with a cam track A'; B, a rotatable platform carried upon said base; and C, grid forming molds carried by said platform.

The base A may be of any suitable construction. In the illustration given, it is provided with legs 10, a main supporting body 11, and a central shaft 12. Suspended below the bed 11 on one side is a motor 13 driving a pulley 14. The pulley 14 drives through a reducing mechanism contained within the housing 15 a shaft 16 which carries at its upper end a pinion 17.

The cam track A' is formed integrally with the bed 11 of base A and it is so shaped as to effect movement of the mold operating devices, as will be later described.

The platform B may also be of any suitable construction. It is carried upon a large gear member 18 which meshes with pinion 17.

Above the gear 18 is a platform member 19 equipped with a hub. It will be noted that this hub together with the central portion of gear 18 are aligned with the hollow shaft 12 of the base and all are rotatably connected by a central shaft 20.

The platform B also provides at its upper portion, bracket supports 21 which carry the molds C.

The molds C are of well known construction and need not be described in detail. The outer mold portion 22 may, if desired, be stationary. The inner mold portion 23 is mounted for move-

ment toward the member 22. Since the internal structure of the molds and their operation are well known, no further detailed description will be given herein.

The mechanism for moving the inner mold part 23 will now be described. The mold part 23 is provided at its rear with two spaced ears 24 receiving between them a bar supporting member 25, the parts being connected by a pivot pin. The bar 25 extends rearwardly and is provided at its rear end with a stop nut 26. A sleeve 27 is slidably mounted on the shank portion of the rod 25, and a spring 28 normally urges the sleeve 27 toward the nut 26. Pivoted 15 secured to the sleeve 27 is a crank arm 29 pivotally carried upon the bracket 30 fixed to and extending through an opening in the platform B. The pivot pin is indicated by the numeral 31. The lower end of the crank arm 29 is provided 20 with a roller 32 which is received within the cam track A'.

In order to supply gas to the molds, I provide a central gas line 33 which extends into a bracket cage 34. In the cage 34, it is connected 25 by a ball joint connection 35 to a pipe 36. Pipe 36 is fixed at its upper end to a head 37 carried by the rotatable platform B. Thus the upper pipe 36 rotates while the lower pipe 33 does not, a gas pipe connection being provided between 30 the two by the ball joint 35. Leading from the top manifold 37 are gas pipes 38 leading to the various molds, as shown more clearly in Fig. 1.

Operation

In the operation of the device, the motor 13 drives the pulley 14, which through gear and worm reducers drives the vertical shaft 16. The pinion 17 carried by shaft 16 causes a rotation of the large gear 18. By this movement, the upper platform B is caused to rotate upon base A.

As the platform rotates, each of the molds is filled, one at a time, by suitable molten metal pouring devices, which are well known in the art and which are not herein described. For the filling operation, the particular mold brought next to the filling device is held in closed position, the cam trackway A' pushing the lower end of the crank arm 29 to the position shown at the left in Fig. 2. After the filling operation, the platform B continues to rotate and the cam track A' swings the crank arm 29 to a position such as illustrated at the right of Fig. 2, in which position the grid is free to drop from the mold and on to a suitable slide or conveyor (not shown).

With the structure shown, it will be noted that

the timing is maintained by means of a single camway A', and the crank arms which engage the cam serve not only as a means for opening and closing the grids, but for steadyng and supporting the upper platform upon the base A.

The structure is extremely simple, but highly efficient in timing the operations and in the low expenditure of power. The crank arms engaging the movable parts of the molds follow surely the trackway while at the same time serving to steady the platform upon the base.

The spring 28 permits relative movement between the crank arm 29 and the mold 23, thereby preventing injury to the parts.

It will be noted that the mold 23 is pivotally mounted so that it may be swung to a raised position for inspection or for removal.

While in the foregoing description, I have set forth certain details, it will be understood that such details in construction and operation may be widely departed from by those skilled in the art while still using the spirit of my invention. I wish it to be understood that I do not desire to be limited to the exact details of construction shown and described, for obvious modifications will occur to a person skilled in the art.

I claim:

1. In a grid casting machine of the character set forth, a base equipped with a cam track, a motor carried by said base, a platform rotatably mounted on said base, means driven by said motor for rotating said platform, spaced molds carried by the platform and comprising fixed outer portions on the outer periphery of the platform and movable inner portions on the inner side of said fixed portions, a plurality of arms secured to said molds, each of said arms being pivotally attached at one end to the inner portion of a mold to tiltably support the same, said arms extending inwardly towards the central portion of

the platform and being movable longitudinally towards and away from the central portion of the platform, means for preventing lateral horizontal movement of said arms while permitting vertical movement thereof, and a plurality of levers pivotally mounted on the platform and having their lower ends engaging the cam track, said levers having their upper ends connected to the free ends of said arms whereby rotation of the platform and the resulting movement of the lower ends of the levers in the cam tracks causes the arms to move longitudinally and the inner portions of the molds to be drawn towards and away from the outer portions thereof.

2. In a grid casting machine of the character set forth, a base equipped with a cam track, a motor carried by said base, a platform rotatably mounted on said base and having its periphery extending beyond said cam track, means driven by said motor for rotating said platform, spaced molds carried by said platform and comprising fixed outer portions on the outer periphery of the platform and movable inner portions on the inner side of the fixed portions, a plurality of arms radially disposed with respect to said platform, each of said arms being pivotally attached at one end to the inner portion of one of the molds to tiltably support the same, a plurality of levers pivotally mounted on the platform intermediate the center and peripheral portions thereof and having their lower ends extending downwardly into engagement with the cam track whereby the levers furnish support for a portion of the platform, a sleeve slidably mounted on each of said arms, each sleeve being pivotally secured to the upper end of one of said levers, and spring means for providing a yielding engagement between each of the arms and the lever secured to the sleeve thereon.

ALVY C. YERKEY.
